UNITED STATES PATENT OFFICE.

WILLIAM STANLEY, OF GREAT BARRINGTON, MASSACHUSETTS, ASSIGNOR TO GENERAL ELECTRIC COMPANY, A CORPORATION OF NEW YORK.

ELECTRIC HEATING-RECEPTACLE.

976,944.

Specification of Letters Patent. Patented Nov. 29, 1910.

Application filed May 13, 1909. Serial No. 495,752.

To all whom it may concern:

Be it known that I, WILLIAM STANLEY, a citizen of the United States, residing at Great Barrington, county of Berkshire, 5 State of Massachusetts, have invented certain new and useful Improvements in Electric Heating-Receptacles, of which the following is a specification.

This invention relates to electric heaters, 10 such as fluid receptacles and the like, and has for its object the provision of a device of this character in which the bottom of the receptacle is cast onto a sheet metal body so as to render the body rigid.

15 One of the objects of my invention is to produce an electric heater having a cast metal bottom into which the heating unit may or may not be cast.

In carrying out my invention, I take a 20 sheet metal blank having the center cut out or perforated and cast a center of substantial thickness into this blank. This cast-in center may in some cases contain the resistance unit and in others the unit is clamped 25 to a cast metal base. After the bottom is cast into the blank, the blanks may be stored away and when it is desired to get them ready for use the metal is spun around the base so as to form a receptacle.

30 Other objects of my invention will appear in the course of the following specification, in which I have shown my invention embodied in concrete form for purposes of illustration.

35 In the drawings disclosing my invention, Figure 1 represents a fragmentary view of a blank with a cast-in center forming a bottom; Fig. 2 represents an end view of the same partly in section; Fig. 3 represents a 40 view of the lower part with the metal spun up around the bottom and the unit clamped thereto; Fig. 4 represents a sectional view of the device in which the resistance conductor is cast into the bottom; and Fig. 5 represents 45 an outside view of the receptacle the lower outer casing being in section.

Referring to the drawings, 10 represents a circular disk or blank which may be of any desired metal, as aluminum, which is 50 easily bent or spun into shape. This is perforated by having its center cut out in the form of a ring and is also provided with perforations 12 around the cut out portion. In the center of this disk I cast a bottom 13 55 which may be of soft metal, as aluminum, or

may be of cast iron. The metal is poured so as to form on both sides of the disk by passing through a central opening from the perforations. By means of these openings the metal is held rigidly in place. This 60 blank shown in Figs. 1 and 2 may be conveniently stored without occupying any considerable space. When it is desired to make use of the same, the metal is bent up and spun around the bottom. In this way a receptacle is formed having an extremely rigid body which will not buckle or change its shape upon changes of temperature. The metal may be corrugated to form screw threads 14. A self-contained heating unit 70 15 may be clamped thereto by means of a screw threaded base 16.

In Figs. 4 and 5 I have shown an arrangement in which the resistance conductor is cast directly into the bottom of the receptacle. In this case, the particular form of unit may be of the type disclosed in my previous application, Serial No. 495,753, filed May 13, 1909, the resistance conductor being inclosed in a metallic shield 17 which is 80 cast into the bottom 18, as shown, and an insulating ring 19 secured to the bottom by means of bolts 20 for supporting the terminal pins 21. In this case the legs 22 are secured to the casing 23 which is screw- 85 threaded at 24 to engage the receptacle.

By means of my invention, an exceedingly good connection of the heating unit to the metal of the receptacle is made possible at all times and the heaters may be stored in 90 any convenient manner without taking up a great amount of storage room.

While I have described my invention as embodied in concrete form for the purpose of illustration, it should be understood that 95 I do not limit my invention thereto, since various modifications thereof will suggest themselves to those skilled in the art without departing from the spirit of my invention, the scope of which is set forth in the 100 annexed claims.

What I claim as new and desire to secure by Letters Patent of the United States, is:—

1. The process of forming electrically heated utensils which consists in securing a 105 heating unit to a flat sheet of metal and bending the metal around the unit to form a receptacle.

2. The process of forming electrically heated utensils which consists in casting an 110

electric heating unit to a sheet of metal and bending the metal around the unit to form a receptacle.

3. The process of forming electrically heated utensils which consists in securing a heating unit in the center of a circular metallic disk and then bending the metal around the unit to form a receptacle.

4. The process of forming electrically heated utensils which consists in casting an electric heating unit in the center of a circular disk and then bending the metal around the unit to form a receptacle.

5. The process of forming electrically heated utensils which consists in casting a flat heating unit in the center of a circular disk of sheet metal and spinning the metal around the unit to form a receptacle.

6. An electric heater comprising a flat, circular metallic disk having a heating unit 20 cast in the center.

7. An electric heater comprising a flat, perforated metallic disk having a flat heating unit cast in the center thereof so that the cast metal extends through the perforations. 25

8. A fluid receptacle comprising a sheet metal body having a metallic bottom cast therein and an electric heating device for said bottom.

In witness whereof, I have hereunto set 30
my hand this 6th day of May, 1909.

WILLIAM STANLEY.
